UNITED STATES PATENT OFFICE.

CHARLES McCARTER, OF DECATUR, ILLINOIS, ASSIGNOR OF ONE-HALF TO CHARLES F. EVANS, OF DECATUR, ILLINOIS.

CAR-MOVER.

1,269,471.

Specification of Letters Patent. Patented June 11, 1918.

Application filed October 5, 1917. Serial No. 194,887.

To all whom it may concern:

Be it known that I, CHARLES McCARTER, a citizen of the United States, and a resident of Decatur, in the county of Macon and State of Illinois, have invented a new and Improved Car-Mover, of which the following is a full, clear, and exact description.

The object of the invention is to provide a simple, efficient and easily manipulated car mover which is characterized by a frame having rollers for engaging the car rails, with means on the top of the frame for engaging the sides of a car wheel to increase the stability of the mover.

Another characteristic of the invention is to increase leverage by compounding same, said levers being disposed obliquely to increase the stability of the mover and facilitate the manipulation of coupled cars.

Other characteristics of the invention will appear as the description proceeds.

In the accompanying drawings, forming part of the application, similar characters of reference indicate corresponding parts in all the views.

Figure 1 is a side elevation of my invention as applied to a car wheel to move a car;

Fig. 2 is a plan view;

Fig. 3 is an end elevation;

Fig. 4 is a horizontal section on line 4-4, Fig. 1;

Fig. 5 is a vertical section on line 5-5, Fig. 1 in which the jaws of the mover are shown in end elevation; and

Fig. 6 is a section similar to that shown in Fig. 4, illustrating the simultaneous operation of the two ends of the clamp.

Referring to the drawings, 7 is a carriage mounted on flanged wheels 8 adapted to roll on a rail 9 of a track. The carriage 7 has a head 10 at the top extending laterally to each side of the carriage and having at each lateral end a horizontal slot 11 converging toward the rear of the carriage and in a vertical plane with a lug 12 provided on a bracket 13 extending rearwardly of the carriage, there being two lugs 12 each in vertical plane with a corresponding slot. This arrangement allows the use of the car mover on either the right or left side of the track, as will appear hereinafter.

An operating lever 14 is pivotally mounted in one of the slots 11. In consequence,

said lever is disposed at an angle to the carriage and helps to balance the mover on the rollers. The end of the longer arm of the operating lever 14 extends beyond the lug 12 which is in vertical plane therewith, and which end is connected by links 15 to a socket 16 of a manipulating lever 17, and which socket is, in turn, connected pivotally to the lug 12 with which the operating lever 14 is in plane. The manipulating lever is, in consequence, disposed angularly to the carriage and makes it possible to separate coupled cars with plenty of clearance for the lever 17. This connection of the levers increases the leverage of the operating lever 14.

The other end of the operating lever 14 is connected to a cam 18 by a link 19 to move said cam on its trunnion 20, carried by a wheel grip or clamp 21, so as to bring said cam 18 against the face of a flange 22 of a car wheel 23. The trunnion 20 has a lug 20' at the free end of same for which the cam 18 has a slot 18' to allow the engagement of the cam with the trunnion. This lug 20' normally prevents the disengagement of the cam from the trunnion. The wheel grip 21 extends transversely of the wheel 23 below the head 10, and presents a fixed jaw 24 at the end opposite where the cam 18 is provided. The jaw is adapted to engage the outer edge of the wheel rim. Preferably a gripping member 25 is provided in the jaw 24.

The clamp or wheel grip has oppositely disposed ears 26 at the fixed jaw 24. The upper ear 26 is engaged by a rod 27 which projects through the frame of a roller carrier 28 bolted to the head 10. The rod 27 carries a spring 29, one end of which abuts against the carrier 28 while the other abuts against a shoulder 30 formed on the rod 27. The carrier 28 supports rollers 31 on each side of the wheel and steadies the carriage 7 on the rail.

The wheel grip 21 has also ears 32 between the ends on each face, the upper ear 32 is engaged by a rod 33 which projects through the slotted end 34 of a lever 35 pivotally suspended between its ends on the roller carrier 28. The upper end of the lever 35 is provided with a head 36. By applying pressure to the lever 35 the clamp is opened and

the car mover may be brought into engagement with the wheel or released from same when the car mover is to be disengaged.

As the manipulating lever 17 is actuated motion is imparted to the operating lever 14 which will, in the downward movement of the manipulating lever 17, bring the movable jaw or cam against the flange of the wheel, in consequence, bringing the gripping member 25 of the fixed jaw against the edge of the rim of the wheel, thereby gripping the wheel and imparting to it a rotary movement as the manipulating lever 17 is moved downward. The initial upward movement of the lever 17 disengages the cam 18 from the flange of the wheel and thereby releases the grip of the clamp on the wheel. The wheel grip 21 is prevented from following the operating lever 14 by the spring 29 mounted on the rod 27. The lever 35 is used only when the mover is to be engaged or disengaged from the wheel of a car. The wheel grip 21 has a rear extension 37 which bears on the front part of the carriage 7 and maintains said wheel grip at the wheel 23. The double sets of ears on the wheel grip allow the use of the mover on either side of the track in conjunction with the double lugs 12 and double slots 11.

In Fig. 6 a wheel grip 21' is provided with a movable jaw or cam 18 at each end of the wheel grip. Each of the cams or movable jaws is suspended from a corresponding operating lever 14 each pivotally mounted in a corresponding slot 11 in the head 10 of the carrier. One of the levers 14 is connected to the other lever 14 to move therewith when said other lever 14 is operated by the manipulating lever 17. In this arrangement the rod 27 and ears 26 may be dispensed with.

I claim:

1. A car mover comprising a carriage, a lever fulcrumed on the carriage and disposed diagonally thereon not to decrease the stability of said carriage, a wheel grip suspended from the carriage and operable by said lever, and a second lever connected to the carriage and to the first lever, said second lever being also disposed diagonally of the carriage so as to facilitate the working of the mover in close quarters.

2. A car mover comprising a carriage adapted to be supported on a rail of a track, a first-class lever mounted diagonally on the carriage so that the stability of the carriage on the rail is not materially affected by said lever, means on the top of the carriage for engaging the sides of a car wheel to steady the carriage on the rail, a wheel grip suspended from the carriage and operable by said lever, and a lever of the second class

secured to the carriage and engaging the lever of the first class and whereby said lever of the first class is operated.

65

3. A car mover comprising a carriage, a lever of the first class disposed diagonally on said carriage, a wheel grip suspended from the carriage and operable by the lever, and a lever of the second class disposed diagonally on the carriage in alinement with the first and connected to the said first lever whereby the same is operated, the diagonal position of said second lever permitting the working of the car mover in close quarters.

75

4. A car mover comprising a carriage, a lever disposed on said carriage, a wheel grip, means connecting the wheel grip to the lever for operating the wheel grip, and a yielding connection from the wheel grip to the carriage for resisting the movement of the wheel grip toward the top of the carriage.

80

5. A car mover comprising a carriage, a lever on said carriage, a wheel grip adapted to be disposed transversely of the carriage below the top of same, means connecting one end of said wheel grip to the lever, a rod connecting the other end of the wheel grip to the carriage to limit the downward movement of the wheel grip, and a spring on said rod for resisting an upward movement of the wheel grip when the other end of the wheel grip is drawn upwardly by the lever.

95

6. In a car mover, a carriage having a head extending laterally to each side of the carriage, said head having a diagonal slot in the lateral ends for receiving a lever, said slots converging toward the rear of the carriage, and a bracket in the rear of the carriage having lugs disposed diagonally so that a slot and a lug are in common vertical plane.

100

7. A car mover comprising a carriage, a lever fulcrumed on the carriage, a wheel grip suspended from the carriage and operable by said lever, and a second lever connected to the carriage and to the first lever, said second lever being disposed diagonally of the carriage to facilitate the working of the mover in close quarters.

110

8. A car mover comprising a carriage, a first-class lever fulcrumed on the carriage, a wheel grip suspended from the carriage and operable by said first-class lever, and a lever of the second class fulcrumed on the carriage and connected to the lever of the first class for operating the same.
